(57) **CLAIM**

The ornamental design for a nasal spray apparatus, as shown and described.

DESCRIPTION

FIG. 1 is a front and top perspective view of the nasal spray apparatus showing the new design;

FIG. 2 is a front view thereof;

FIG. 3 is a rear view thereof;

FIG. 4 is a side view thereof;

FIG. 5 is a top view thereof; and,

FIG. 6 is a bottom view of thereof.

The portions of the nasal spray apparatus shown in broken lines form no part of the claimed design.

1 Claim, 4 Drawing Sheets

FIG. 1

FIG. 2

FIG. 3

FIG. 4

FIG. 5

FIG. 6
